RHEOSTAT

Bennett M. Leece, Shaker Heights, Ohio, assignor
to The Leece-Neville Company, Cleveland,
Ohio, a corporation of Ohio

Application December 11, 1941, Serial No. 422,539

9 Claims. (Cl. 201—48)

This invention relates generally to voltage regulators for use with various types of electrical generating apparatus including the generators which supply current to the auxiliary equipment on aircraft and other motor vehicles. More particularly, the invention relates to a novel rheostat for use in such voltage regulators and for other purposes.

Voltage regulators of the electromagnetic type have been used heretofore with the generators of aircraft and other motor vehicles and many of such devices have operated on the principle of intermittently connecting a resistance of fixed value into, and disconnecting the same from, the generator field circuit by the use of cooperating contacts which are rapidly opened and closed by a vibratory armature. During recent times, however, the number of electrically operated auxiliary devices used on aircraft and other motor vehicles have been extensively increased and the generators have likewise been increased in size or rating to supply the necessary power to such auxiliaries. In attempting to apply the electromagnetic vibratory-contact type of regulator having a field resistance of fixed value to such generators of increased size, I have found that due to the relatively large current variations in the field circuit, the vibratory contacts of the regulator have frequently been subjected to destructive burning as the result of sparking occurring at this point. The present invention provides an improved rheostat for use in such voltage regulators and which enables such regulators to operate more efficiently and satisfactorily with generators of higher rating and substantially eliminates such sparking and burning.

An object of my invention is to provide an improved construction for a rheostat of the kind having a rocking contact member.

Another object of this invention is to provide an improved rheostat of the kind mentioned in which novel means is employed for retaining the rocking contact in proper cooperation with the stationary contact member.

The invention may be further briefly summarized as consisting in certain novel combinations and arrangements of parts hereinafter described and particularly set out in the appended claims.

In the accompanying sheet of drawings:

Fig. 1 is a plan view of a rheostat constructed according to my invention;

Fig. 2 is a partial perspective view showing the means for retaining the rocking contact member in position; and

Fig. 3 is a wiring diagram showing the rheostat employed in voltage regulation.

Further reference will now be made to the drawing for the purpose of describing my improved rheostat and its operation in greater detail. Before proceeding with the detailed description, however, I wish it to be understood that the invention is not to be considered as limited to the particular rheostat illustrated and described, but should be regarded as embracing various other similar devices coming within the scope of the appended claims.

As shown in Figs. 1 and 3, my improved rheostat is embodied in a voltage regulator having a base 10 which forms a mount or support for a relay 11 and a field resistance 12. The relay 11 may comprise a substantially L-shaped frame 13 of magnetizable material and a magnet 14 mounted on an arm 13a of such frame with its core 15 extending substantially parallel to the arm 13b of the frame. The core 15 carries coils or windings 16 and 17 which will be described hereinafter. The relay 11 also includes an armature 18 pivotally connected with the frame by the pivot pin 19, and a pair of cooperating contact members 20 and 21 which control the auxiliary circuits of the generator 22 and the energization of the coils 16 and 17.

The armature 18 may be in the form of a bell crank lever having one arm portion which extends across the core 15 and another arm portion which extends generally parallel with the arm portion 13b of the frame and may have a tension spring 23 connected therewith. The tension of the spring 23 may be varied as desired by means of the adjusting screw 24.

The contact member 20, which in this instance is shown as the stationary contact member, comprises a row of individual contact elements or segments 25 separated from each other by intervening insulating pieces 26. The segments 25 and the insulating pieces 26 may be arranged in a row or pile and may be held together by means of a clamping screw 27 extending therethrough and which is suitably insulated from the segments. The contact member 20 may also include a backing plate 28 which is spaced from, or otherwise insulated from, the segments 25 and has its ends connected to a pair of end blocks 29a and 29b formed of insulating material and in which the head and nut of the clamping screw 27 may be recessed. The contact member 20 may be suitably mounted on the base 10 so as to extend transversely of the outer end of the armature 18 and in substantially parallel

relation to the resistor 12. The individual segments 25 are connected with the resistor 12 at spaced points therealong by a plurality of taps 30. The first or initial segment 25a of the row may be connected with one end of the resistor 12 by the tap 30a and the last segment of the row may be connected with the other end of the resistor by the tap 30b.

The movable contact member 21 is in the form of a curved metallic bar or rocker which has rocking engagement with the row of segments 25 of the stationary contact member 20. The curvature of the contact member 21 is preferably such that it will engage at least two of the segments 25 at one time as its point of engagement with the contact member 20, and this point of contact will travel back and forth along the contact member 20 as rocking movement is imparted to the contact member 21 by the armature 18.

As shown in the drawing, the contact member 21 is connected with the outer end of the armature 18, and while this may be accomplished in various ways, I show in this instance a forked portion or U-shaped member 31 which is suitable connected to the curved contact member substantially at the midpoint of the latter as by means of solder or the screw 32. The U-shaped member 31 thus forms a substantially rigid projecting arm or lever portion on the back of the curved contact member 21 by which this contact member can be rocked on the segments 25.

An anti-friction bearing 33 mounted on the outer end of the armature engages in the recess of the U-shaped member 31 and provides a freely movable operating connection between the armature and the curved contact member 21. With the arrangement just described, it will be seen that when the magnet 14 is sufficiently deenergized, the armature 18 is shifted away from the magnet core 15 by the spring 23 and the contact member 21 will be rocked toward the left, as seen in Figs. 1 and 3, and the point of engagement with the contact member 20 will shift toward the end contact element 25a. Likewise, when the energization of the magnet 14 is increased sufficiently and the armature 18 is drawn toward the magnet core, the contact member 21 will be rocked in the opposite direction and the point of contact will travel toward the end segment 25b.

To prevent the contact member 21 from sliding or "walking" on the contact member 20, I provide a retaining means which may be in the form of an elongated flat spring 35 having one end thereof connected to an end of the contact member 21, as indicated at 36, and its opposite end anchored to the other or remote end of the contact member 20, as by means of the screws 37 connecting the same to the insulating block 29b. The spring 35 is constructed with a rectangular opening 38 therein of a size and shape to permit the contact member 21 to extend through the spring for cooperation with the segments of the contact member 20. The spring 35 thus holds the contact member 21 against creeping or shifting in any direction relative to the contact member 20 and yet permits the contact member 21 to have the desired rocking contact with the row of segments 25.

In addition to the retaining spring 35, I may provide means for pressing the contact member 21 against the contact member 20 so that good electrical contact will be obtained therebetween.

This pressure means may comprise tension springs 39 which are anchored on the contact member 20 adjacent the ends thereof by being connected to ears 28a provided on the backing plate 28 and are connected with extension pieces 21a provided at the end of the contact member 21.

In Fig. 3 I show my rheostat being used in connection with voltage regulation and embodied in an electrical system containing a generator 22. The various circuit connections can be best described by referring to the wiring diagram shown in Fig. 3. As shown in this diagram, the generator 22 has a shunt field winding 40 which has one end connected with the brush 41 and its other end connected with the rocking contact member 21 by the conductor 42. The winding 16 of the regulator is a voltage coil having one end connected with the brush 43 of the generator 22 by the conductor 44 and its other end connected with the brush 41 of the generator by the conductor 45. The winding 17 is a bucking coil, that is, a coil which magnetically opposes the coil 16. One end of this coil is connected with the brush 43 of the generator by the conductor 44 and its other end is connected with the brush 41 by a circuit extending through the conductor 46 to the point 45a and then through a portion of the field circuit and the shunt field winding 40. In the field circuit the brush 43 of the generator is connected with one end of the resistor 12 through a portion of the conductor 44 and through the conductors 47 and 48. The point 45a, with which one end of the bucking coil 17 of the relay is connected by the conductor 46, is connected with an intermediate tap or point 12a of the resistor 12 by means of the short conductor 49. A resistance 50 of suitable value connects the conductor 47 with the point 45a and extends in parallel circuit relation with the conductor 48 and an adjacent end section 12b of the resistor 12. An external circuit or load may be connected with the terminals of the generator through the pair of load conductors 51.

When the generator 22 is about to be started up, the magnet 14 of the regulator is substantially deenergized and the armature is held away from the core 15 by the spring 23, and the point of contact between the contact member 21 and the stationary contact member 20 will be at the end segment 25a. With the contact member 21 in this position, it will be seen that none of the resistance provided by the resistor 12 will be included in the field circuit, and hence the generator will receive full field excitation during the starting thereof. The field circuit at this time will extend from the brush 43, through a portion of the conductor 44, through conductors 47 and 48, through tap connection 30a, to end segment 25a, and then through contact member 21, conductor 42, and through the field winding 40, back to the brush 41 of the generator.

As the speed of the generator increases, its terminal voltage will build up, thus increasing the energization of the winding 16 of the regulator magnet 14. This will cause the armature 18 to be drawn toward the core 15, and the resulting rocking of the contact member 21 will cause the point of contact with the member 20 to travel toward the right along the segments 25 a distance corresponding with the section of the resistor 12 which is needed in the field circuit to hold the terminal voltage substantially constant. At this time, the field current will be divided and

the two portions will flow respectively through the resistance section 12b and the parallel resistor 50.

If the speed of the generator 22 decreases, the energization of magnet winding 16 likewise decreases and permits the spring 23 to rock the contact member 21 toward the left, thereby decreasing the length of the section of the resistor 12 which is contained in the field circuit. During the operation of the generator 22, the contact member 21 will be rocked back and forth on the segmental contact member 20 in accordance with changes in the speed of the generator, and when the contact member 21 has been moved a distance sufficient to compensate for the change, it will remain relatively stationary to hold the terminal voltage of the generator at the desired value until another change in generator speed occurs. The contact member 21 will also be rocked in a similar manner on the segmental contact member 20 whenever the load on the generator changes sufficiently to alter the speed or terminal voltage.

During the operation of the generator the contact member 21 has appreciable rocking movement on the contact member 20 only when changes occur in the speed or load of the generator, but it may have a small amount of vibratory movement either continuously or from time to time which may be only sufficient to shift the point of engagement to one or the other of a pair of adjacent segments 25. This relatively small vibratory movement of the contact member 21 will be sufficient to compensate for slight variations and will maintain the terminal voltage substantially constant.

As mentioned above, the magnet winding 17 is a bucking coil which magnetically opposes the coil 16. The purpose of the winding 17 is to render the regulator more accurately responsive to changes in the load or speed of the generator and more effective in compensating for such changes. I have observed that the hysteresis effect, occurring in the frame and armature of the relay as changes in magnetization take place, tends to produce an undesirable variable action in the regulator because the hysteresis effect is different when the speed of the generator is increasing from what it is when the speed of the generator is decreasing. I have found that this undesirable action of the regulator resulting from the hysteresis effect in the magnet frame and armature can be largely overcome or compensated by the use of the bucking coil 17.

As pointed out above, one end of the bucking coil 17 is connected with the brush 43 of the generator by the conductor 44 and its other end is connected with the intermediate point 12a of the resistor by the conductors 46 and 49. From this intermediate point of the resistor, the return circuit for the winding 17 is coextensive with the portion of the field circuit which extends through the contact members 20 and 21, the conductor 42, and the field winding 40, to the brush 41.

During the operation of the regulator, the energization of the bucking coil 17, and hence its effectiveness as a regulating force or factor, will vary as the point of engagement of the contact member 21 shifts along the contact member 20. In general, the energization of the bucking coil increases when the speed or load of the generator decreases and decreases when the speed or load of the generator increases. In the present form

of my apparatus as shown in the drawing, the bucking coil will be of maximum effectiveness when the contact member 21 is on segment 25b of the contact member 20 which is connected with the point 12a of the resistor 12 because at this time the resistance of the bucking coil circuit is a minimum. As the contact member 21 shifts toward the right from the segment 25b, the effectiveness of the bucking coil decreases and when the contact member 21 shifts toward the left from the segment 25b, the effectiveness of the bucking coil increases.

It is important to observe that in the operation of my regulator, the contact member 21 always maintains electrical contact with the contact member 20 and there is no opening and closing of the field and regulator circuits at this point as has been the case heretofore with regulators of the vibratory type. Since these circuits are always maintained at the contact members 20 and 21, there will be little likelihood of the contact members being burned or pitted as the result of sparking at this point.

25 While I have illustrated and described my im-
proved regulating apparatus and rheostat in a
more or less detailed manner, it will be under-
stood, of course, that I do not wish to be limited
to the particular details and arrangements here-
in described, but regard my invention as includ-
30 ing such changes and modifications as do not
constitute a departure from the spirit of the in-
vention and the scope of the appended claims.

Having thus described my invention, I claim:

- 35 1. In a rheostat, a member comprising a series
of spaced contacts, a resistor having taps connected with said contacts, a curved contact member rockable on said spaced contacts, a flexible retaining strip overlying said contacts and having one end attached to one end of said curved contact member, and its other end anchored to the opposite end of the first-mentioned member, said strip permitting such rocking of said curved contact member but resisting longitudinal shifting of the latter relative to said contacts and having an opening therein exposing the contacts for engagement by said curved contact member, and means for imparting rocking movement to said curved contact member.

40 2. In a rheostat, a member comprising a series
of spaced contacts, a resistor having taps connected with said contacts, a curved contact member rockable on said spaced contacts, a flexible retaining strip overlying said contacts and having one end attached to one end of said curved contact member and its other end anchored to the opposite end of the first-mentioned member, said strip permitting such rocking of said curved contact member but resisting longitudinal shifting of the latter relative to said contacts and having an opening therein exposing the contacts for engagement by said curved contact member, a pair of tension springs connected with the ends of said curved contact member for drawing the same against said contacts, and means for imparting rocking movement to said curved contact member.

45 3. In a rheostat, a member having a series of contacts insulated from each other, a curved contact member rockable on said series of contacts, a flexible strip connecting said curved member with the first-mentioned member so as to permit such rocking of said curved member but resisting longitudinal shifting of said curved member relative to said series of contacts, and a pair of springs

50

55

60

65

engaging the ends of said curved member and acting to hold the same against said first-mentioned member.

4. In a rheostat, a member having a series of contact segments insulated from each other, a resistor having taps connected with the respective segments, a rocker-shaped contact element rockably engaging said segments, and a flexible retaining strip connected with one end of the first-mentioned member and with the other end of said rocker-shaped element, said strip permitting such rocking engagement by said rocker-shaped element but resisting longitudinal shifting of said rocker-shaped element relative to said series of segments.

5. In a rheostat, a member having a series of contact segments insulated from each other, a resistor having taps connected with the respective segments, a rocker-shaped contact element rockably engaging said segments, and a flexible retaining strip connected with one end of the first-mentioned member and with the other end of said rocker-shaped element so as to permit such rocking engagement by said rocker-shaped element but resisting longitudinal shifting of said rocker-shaped element relative to said series of segments, said strip having an opening therein exposing said segments for engagement by said rocker-shaped element.

6. In a rheostat, a member having a series of contacts insulated from each other, a curved contact member rockable on said series of contacts, a flexible strip connecting said curved member with the first-mentioned member, and a pair of springs engaging the ends of said curved member and acting to hold the same against said first-mentioned member, said strip permitting such rocking of said curved member but resisting longitudinal shifting of said curved member relative to said series of contacts and having an opening therein exposing said contacts for engagement by said curved member.

7. A rheostat comprising a member having a series of contact segments insulated from each other, a curved contact member rockably engaging the first member, a resistor having taps con-

nected with said segments, a flexible retaining strip having one end thereof connected with one end of the first member and its other end connected with the opposite end of said curved member, said strip permitting such rocking of said curved member but resisting longitudinal shifting of said curved member relative to said series of segments, a magnet having a coil and a movable armature, and means connecting said armature with said curved member for actuating the latter.

8. A rheostat comprising a member having a series of contact segments insulated from each other, a curved contact member rockably engaging the first member, a resistor having taps connected with said segments, a flexible retaining strip having one end thereof connected with one end of the first member and its other end connected with the opposite end of said curved member, said strip permitting such rocking of said curved member but resisting longitudinal shifting of said curved member relative to said series of segments, a magnet having a coil and a movable armature, a forked portion on the concave side of said curved member adjacent the midpoint thereof, and an antifriction bearing in said forked portion and connecting said curved member with said armature.

9. In a rheostat, a resistor having a row of contact elements, a curved contact member, a pair of tension springs engaging the ends of said curved member and holding the same in rocking engagement with said contact elements, a flexible retaining strip connected with said curved member and having an opening exposing said elements for engagement by said curved member, said strip permitting such rocking of said curved member but resisting longitudinal shifting of said curved member relative to said row of contact elements, a magnet having a coil and a movable armature, a forked portion on the concave side of said curved member adjacent the midpoint thereof, and an antifriction bearing in said forked portion and connecting said curved member with said armature.

BENNETT M. LEECE.
